UNITED STATES PATENT OFFICE.

OTTO MAUSSNER, OF COLLINGSWOOD, NEW JERSEY.

DESIGN FOR A KNIFE-HANDLE.

SPECIFICATION forming part of Design No. 35,482, dated December 24, 1901.

Application filed November 13, 1901. Serial No. 82,164. Term of patent 3½ years.

To all whom it may concern:

Be it known that I, OTTO MAUSSNER, a subject of the King of Great Britain, residing at Collingswood, in the county of Camden and State of New Jersey, have invented and produced a new and original Design for Knife-Handles, of which the following is a specification, reference being had to the accompanying drawing, forming part thereof.

6 The figure of the drawing is a plan view of a knife-handle, showing my new design.

As shown in the drawing, the leading or material feature of my design comprises a portrait A, representing the late President McKinley, surrounded by a wreath B, with a representation C of the United States flag above

and a scroll D beneath the same. Above the flag is a star E, from which pencils of light F are thrown downward.

Having described my invention, what I claim as new, and desire to secure by Letters Patent, is—

The design for a knife-handle, substantially as shown and described.

In testimony whereof I have signed my name to this specification in the presence of two subscribing witnesses.

OTTO MAUSSNER.
